FIG. 6.

INVENTOR:

George W. Denison,

By Rake Maeslin, Fitch's.

UNITED STATES PATENT OFFICE.

GEORGE W. DENISON, OF CLEVELAND, OHIO.

WALL CONSTRUCTION.

1,343,312.

Specification of Letters Patent. Patented June 15, 1920.

Application filed April 23, 1918. Serial No. 230,318.

To all whom it may concern:

Be it known that I, GEORGE W. DENISON, residing at Cleveland, in the county of Cuyahoga and State of Ohio, have invented 5 a certain new and useful Improvement in Wall Construction, of which the following is a full, clear, and exact description, reference being had to the accompanying drawings.

0 In the building of walls with hollow tiles it is desirable to have the voids in the tiles extending horizontally so that extended surfaces are provided for the mortar. However, at corners or at jambs it is necessary 5 to wall off the ends of the voids, which is ordinarily effected by placing short tile sections of the proper height on end. As tiles have heretofore been constructed this usually requires special sizes of tile for use 0 at the corners and jambs or entails loss of material and waste of time if the mason breaks the desired short length from a standard tile.

The object of my invention is to provide 5 a rectangular tile adapted for laying on edge or flatwise, horizontally, in the running course, of walls of various thicknesses and so proportioned and arranged that it may be readily severed into a plurality of sections, each of which when stood on end will have the same height as the vertical dimension of the corresponding horizontal running course. This enables the completing 0 of the corners and jambs without waste of time or material and without requiring fine workmanship on the part of the mason.

By using a single block having the capacity of acting in the regular courses where they are laid flatwise or on edge and also severable into sections for end members, I simplify the operation; I reduce the cost of equipment which must be maintained by the manufacturers; I reduce the amount of stock which must be kept in hand, and I reduce the wastage incurred by the builder.

In accomplishing the desired result, I provide a block having a width which is equal to twice the height plus a mortar joint, and I provide a length which is equal to the width plus the height, and I score the block transversely part way through it by a kerf which is located at a distance from one end of the block equal to the height of

the block, and which is also at a distance 55 from the other end equal to the width of the block.

When such a block as described is laid flatwise in a horizontal course it is adapted to have its vertical faces aline with the 60 outer vertical faces of two blocks standing vertically and separated by a mortar joint; when my block is laid on edge its top and bottom faces may aline with the top and bottom faces of two blocks laid flatwise and 65 separated by a horizontal mortar joint; when my block is severed at the kerf one section stood on end may have its edges aline with the four closed faces of a block laid horizontally, and the other section 70 when stood on end may similarly aline with the four outer faces of two blocks separated by a mortar joint.

It will be seen, therefore, that my blocks 75 may be used to build walls of various thicknesses, which walls are bonded by reason of some of the blocks standing on edge and some flatwise, while at the corner or the jambs, to close the space opposite the voids, a block is severed at the kerf and one section 80 is stood on end opposite the adjacent flatwise block and the other section on end opposite the two blocks, and the corner or jamb is completed without wastage.

My invention is clearly illustrated in the drawings hereof, which show the adaptation of the block to several forms of wall. In these drawings, Figure 1 is a perspective of a so-called 12-inch wall sectioned on a 85 vertical transverse plane; Fig. 2 is a similar section of a so-called 8-inch wall; Figs. 3 and 4 are perspectives of corners of such 90 12 and 8-inch walls respectively; Fig. 5 is a perspective of a jamb end of a so-called 8-inch wall. The remaining figures show the block itself, Fig. 6 being an edge view, Fig. 7 a plan and Fig. 8 an end view.

The above drawings show my hollow block in its preferred form, wherein there 100 are two internal webs separated by the thickness of a mortar joint. In such blocks there are three voids extending continuously and without change of dimension throughout the length of the block. The two outer 105 or extreme voids are square in cross section, while the intermediate void has a height equal to either extreme void and a width equal to the thickness of a mortar joint.

The walls of the block, both horizontal and vertical, and the internal webs are all preferably of the same thickness.

Such a block as above described is shown 5 in detail in Figs. 6, 7 and 8, wherein 10 and 11 represent the two narrow sides of the block, which it is convenient to call the edge faces, and 12 and 13, the wide sides of the block, which I sometimes call the top and 10 bottom. 14 and 15 designate the intermediate webs, 16 and 17 the square voids, and 18 the intermediate void.

The distance across the narrow face 10 or 11 I call the height of the block, this dimension being designated A in Fig. 8. Similarly I call the distance across the wide face the width of the block and designate it B in Fig. 8. The distance between the webs is designated D. It will be seen from this 20 figure that the width B is equal to twice the height A plus the thickness of the void 18, or $B=2A+D$. The length (C, Fig. 7) is equal to the sum of the height and the width, or $C=A+B$.

25 At a distance from one end of the block equal to the height of the block (dimension A) I form a kerf 19 which extends transversely of the block through one of its flat faces and into the intermediate webs. The 30 distance of this kerf from the near end of the block (dimension A', Fig. 7) is equal to the height of a block, while the distance from the far end of the block (dimension B', Fig. 7) is equal to the width of the 35 block, these dimensions being equal to the dimensions A and B in Fig. 8.

To bring out more clearly the relation of the various dimensions of the block I will say that I prefer to make the block with the 40 dimension A equal to $3\frac{3}{8}$ inches, B $7\frac{3}{4}$ inches, C $11\frac{3}{8}$ inches, D $\frac{1}{2}$ inch. The thickness of the webs and walls may vary as desired, but a satisfactory width is $\frac{5}{8}$ of an inch, which leaves each square void $2\frac{3}{8}$ inches on each 45 side. The kerf is located $3\frac{3}{8}$ inches from one end and $7\frac{3}{4}$ inches from the other and may conveniently have a depth of between two and three inches.

In Fig. 1 I have shown a so-called 12-inch 50 wall made with repeating multiple courses, each multiple course comprising two blocks laid horizontally opposite the side of one block standing on edge. In the bottom multiple course shown the horizontal blocks 55 as N N' form the left-hand portion of the wall and the edge blocks P the right-hand face, while in the next multiple course, the edge blocks as P' are at the left-hand face and the flatwise blocks as N' N' at the right-hand. The third multiple course shown is 60 laid the same as the first and so on. With such an arrangement the overlapping of the flatwise blocks bonds the whole wall.

Now when it comes to the corner of such 65 a wall as shown in Figs. 1 and 3 there would

naturally be open spaces at the blocks adjacent to the outer face of the wall, such open spaces in the two portions of the wall facing at right angles to each other. To close such spaces I simply take one of my 70 standard blocks and sever it at the kerf and I lay the short sections as Q on end opposite the ends of the blocks N'. As one of these blocks N' at the corner overlaps the corresponding block at right angles to it by an 75 amount equal to the height of a block (dimension A), there would be just room enough in the corner for the block Q to stand with mortar about its inner faces and with its outer faces flush with the two wall 80 faces. Now to fill in the space opposite the ends of the blocks P, I simply use the longer piece of the severed block and stand it on end as shown at R in Fig. 3.

Figs. 2 and 4 illustrate a so-called 8-inch 85 wall wherein there is a horizontal course of blocks S surmounted by two blocks T and T'. At the corner of such a wall the short section Q of the severed block fills the space in the low course, while the large section R 90 completes the tall course.

Fig. 5 illustrates the jamb end of an 8-inch wall where it will be seen that the ends of the flat courses S are closed by two of the short sections Q (the voids of which 95 are vertical as illustrated in dotted lines), while the tall courses T and T' are closed by the longer severed sections R also standing vertically.

The above illustrations show clearly the 100 availability of my block for severance in such a manner as to close openings at the corners and ends of walls without waste. The kerf defines the position of the separation and enables it to be readily made by a 105 mason by means of a blow of his trowel on the face of the block opposite the inner edge of the kerf. At the same time this kerf does not in the least interfere with the load carrying qualities of the wall, for the webs and 110 walls of the block are continuous in the vertical direction, whether the blocks lie flatwise or on edge.

It will be observed that the drawings 115 show one wide and narrow face of each block made smooth and the other wide and narrow face roughened or formed with special surface. This characteristic enables the same block to be laid to present a smooth face or rough face, as desired. This feature, 120 however, is not claimed herein but in my pending application Serial No. 211,488. The wall constructed with my blocks, wherein one block stands opposite the end of the two blocks separated by a mortar joint, is 125 claimed in my pending application Serial No. 181,218.

Having thus described my invention, what I claim is:

1. A wall construction comprising hollow 130

tiles laid with their voids horizontal and some of the tiles lying flatwise and others on edge, each tile having a width equal to twice its height plus the thickness of a mortar joint, and tiles standing on end at the corners or jambs and closing said horizontal voids, such vertical tiles having the same height and width as the other tiles and having two sizes of lengths, one of which is equal to the height of the tile and the other of which is equal to the width of the tile.

2. A wall constructed of hollow building blocks each having three internal voids extending through the block from end to end, the intermediate void being narrow and of the thickness of a mortar joint, each block

having a width equal to twice its height plus the thickness of the narrow void, said tiles in the body of the wall being laid with their voids horizontal and some of the tiles lying flatwise and others on edge, and tiles standing on end at the corners or jambs and closing said horizontal voids, such vertical tiles having the same height and width as the other tiles and having two sizes of lengths, one of which is equal to the height of the tile and the other of which is equal to the width of the tile.

In testimony whereof, I hereunto affix my signature.

GEO. W. DENISON.
